UNITED STATES PATENT OFFICE.

JOHN ELLENSON, OF SUPERIOR, WISCONSIN.

REVOLVING MEAT-BLOCK.

1,088,065.

Specification of Letters Patent. Patented Feb. 24, 1914.

Application filed November 8, 1911. Serial No. 659,180.

To all whom it may concern:

Be it known that I, JOHN ELLENSON, a citizen of the United States, residing at Superior, in the county of Douglas and State of Wisconsin, have invented certain new and useful Improvements in Revolving Meat-Blocks, of which the following is a specification, reference being had therein to the accompanying drawing.

10 This invention relates to chopping blocks and has for its object the production of a chopping block whose chopping surface can be rotated at will, so as to turn the meat to the most convenient and most advantageous 15 position for cutting without having to bodily lift the meat after being once placed on the block.

Another object of this invention is the production of efficient means for raising the 20 body of the block whereby the same may be easily rotated.

Other objects and advantages will appear from the following specification and claims, and, of course, the device can be modified in 25 detail construction without departing from the spirit of the invention.

In the drawings:—Figure 1 is a vertical section of the chopping block. Fig. 2 is a bottom plan view of the block supporting 20 frame. Fig. 3 is a fragmentary bottom plan view of the chopping block. Fig. 4 is an enlarged section of the block supporting frame showing the same attached to the leg. Fig. 5 is a detail perspective of the elevating 25 foot treadle. Fig. 6 is a detail perspective view of the inner end of the lever for raising the chopping block. Fig. 7 is an enlarged sectional view of the chopping block supporting frame showing the construction 40 of the ball bearing race.

Referring to the drawings by numerals 1 designates the chopping block body which carries at its lower face a pintle or pivot member 2. This pivot member 2 is provided with a flattened head 3 which head is seated in a socket 4 formed in the under face of the chopping block 1. Screws 5 pass through the head 3 of the pivot member 2 for securely holding the same in engagement with the chopping block.

A chopping block supporting frame 6 is supported by means of legs 7 which legs have their reduced ends 8 fitted in apertures 9 formed in the frame 6. This frame 6 comprises a circular body 10 which is provided

with reinforcing spokes 11 connected to a central hub 12. These spokes 11 are preferably formed of a T structure in cross section for greatly strengthening the same. The hub 12 is provided with an aperture 13 which receives the pivot member 2 and this aperture 13 is surrounded by a plurality of ball bearing races 14 in which is carried the ball bearings 15. These ball bearings 15 normally engage the base of the races 14, one side thereof and the side of the pivot pin or member 2. It will therefore be obvious that an efficient journal has been produced for the pivot member 2, and also that the friction will be greatly reduced by having the ball bearings engage the side of this member. Pads 16 are carried by the top ends of the legs 7 as is illustrated in Fig. 1, and these pads are preferably formed of rubber for holding the block in a set position when having its lower face resting upon said pad.

A hanger member 17 is secured to the hub portion 12 of the frame 6 and by means of the threaded stem 18. This hanger member 17 is provided with a slot 19 through which passes the lever 20. This lever is pivotally connected to the hanger 17 by means of a pivot pin 21. The inner end of the lever 20 is flattened so as to form a dished supporting surface 22, and in the center of this flattened end is formed a socket 23 which socket is adapted to receive the pointed end 24 of the pivot member 2. The opposite end of the lever 20 is pivotally connected to a foot treadle 25 which treadle is carried by a bracket 26 supported by one of the legs 7. The treadle 25 is provided with a forwardly extending foot engaging portion 27 for allowing the treadle to be easily operated.

When it is desired to rotate the body 1 of the chopping block, the foot treadle 25 is depressed so as to cause the pivot member 2 to be raised by means of the flattened end of the lever 20. When the pivot member 2 is raised from engagement with the pads 16, the body of the block may then be easily rotated owing to the fact that the pointed end 24 is positioned in the socket 23 and since the friction on the pivot member will be greatly reduced by the ball bearings carried within the socket 4, which ball bearings have a vertical movement.

From the foregoing description it will be obvious that an efficient means has been produced whereby the body of the chopping

block may be easily raised so that the same may be rotated to any desired position for facilitating the cutting of meat positioned thereon. It will further be obvious that owing to the rubber pads carried by the upper ends of the legs, an efficient means has been produced for locking the block through its own weight in a set position, upon the chopping block support.

10 By the use of the present device, it will not be necessary to rotate the chopping block to any set position as the same will be securely held at any point upon which the block is lowered so as to rest upon the supporting frame.

Having described the invention what is claimed is:—

1. In a revolving meat block, a stationary stand, a center bearing carried by said stand, a revolving block, a spindle disposed centrally of the block and fitting said bearing, friction pads adjacent the periphery of said stand whereon said block normally rests, and means to lift the block from the

friction pads and permit the revolution of 25 the same.

2. In a device of the kind described, a stand having a centrally disposed opening therein, said opening being provided with spaced annular grooves, a block supporting 30 spindle having a conical lower end, said spindle fitting within said opening and movable longitudinally thereof, balls in said grooves, being smaller than the height of said grooves for allowing the bodily upward movement of the balls within the grooves therefor, forming anti-friction means for said spindle, and a lever pivoted to the stand and provided with a rest at one end wherein the apex of the conical spindle 40 end normally rests.

In testimony whereof I hereunto affix my signature in presence of two witnesses.

JOHN ELLENSON.
